HAIR CURLER

James K. Crotts, Winston-Salem, N. C.

Application December 6, 1941, Serial No. 421,997

8 Claims. (Cl. 132—33)

This invention relates to hair curlers, and has for one of its objects the production of a simple and efficient releasable locking means for a hair curler to hold the rotating hair-gripping jaws in a set and non-rotatable position.

Another object of this invention is the production of a simple and efficient hair-clamping means for use with the rotatable hair-gripping jaws.

Other objects and advantages of the present invention will appear throughout the following specification and claims.

In the drawings—

Figure 1 is a side elevational view of one form of the invention;

Figure 2 is a top plan view of the form shown in Figure 1;

Figure 3 is a longitudinal sectional view taken on line 3—3 of Figure 2;

Figure 4 is a horizontal sectional view taken on line 4—4 of Figure 3;

Figure 5 is a vertical sectional view taken on line 5—5 of Figure 3;

Figure 6 is a perspective view of a further modified form;

Figure 7 is an end view of the form shown in Figure 6;

Figure 8 is a side elevational view of another modified form of the device;

Figure 9 is an end elevational view of the form shown in Figure 8;

Figure 10 is a perspective view of the shield and hair clamp used with the device shown in Figure 8;

Figure 11 is a perspective view of the form shown in Figure 8;

Figure 12 is a vertical sectional view taken on line 12—12 of Figure 11; and

Figure 13 is an enlarged side elevational view partly in section illustrating the form shown in Figures 8, 11 and 12.

By referring to the drawings it will be noted that 15 designates the hair-winding drum which comprises a primary jaw 16 and a secondary jaw 17 is hingedly secured, as at 18, to one end of the primary jaw 16. The jaw 17 is adapted to clamp down over the jaw 16 and to hold the hair in a clamped relation upon the drum 15, as the hair is wound upon the drum. The drum 15 carries a winding knob 19 at one end for the purpose of rotating the drum 15 as the knob 19 is rotated. A hair-guiding member 20 is used in association with the winding drum 15 and this guiding member 20 comprises a journal portion 21 which fits within a longitudinal socket 22 of the drum 15,

as shown in Figure 3. The journal portion 21 is provided at one end with an outwardly extending loop portion 23 which extends beyond the outer end of the drum 15 and is provided with an inclined portion 24 for fitting into the radiating notches 25 formed at one end of the drum 15, as shown in Figures 3 and 5. This loop 23 terminates in an underlying leg 26 which extends under the drum 15 and is provided with an outwardly bent terminal 27 to which is pivotally secured a swinging latch 28. A parallel clamping rod 29 is fixed, as at 30, to the underlying leg 26 and the opposite end of the clamping rod 29 is provided with an outwardly inclined end 31, as shown in Figure 4. This end 31 is adapted to be engaged by the end portion 32 of the latch 28 and holds the rod 29 in clamped parallel relation to the leg 26 when the latch 28 is moved to the position shown in full lines in Figure 4. When the latch 28 is moved to the position shown in dotted lines in Figure 4, the rod 29 may be swung away from the leg 26 to permit the hair which is to be wound upon the drum 15 to be fitted between the rod 29 and the leg 26.

I preferably provide a protector pad 33 of any suitable or desired material similar to that shown in Figure 10 and which fits under the guiding member 20 in actual practice, against the head of the user, and this protector pad 33 is provided with a suitable longitudinally extending slot 34 which is adapted to register with the rod 29 and leg 26.

It should be understood that the pad 33 is placed against the head and a strand of the desired amount of hair is extended through the slot 34 of the protector pad 33 and between the rod 29 and the leg 26, and the latch 28 is moved to a locking position. The end of the hair is then clamped between the jaws 16 and 17 and the drum 15 is rotated, the guiding member 20 moving toward the pad 33 as the hair is wound upon the drum 15. By moving the drum 15 toward the inclined portion 24 of the loop 23, the notches 25 will engage the inclined portion 24 and lock the drum 15 in a set position. The drum may be released by moving the drum 15 away from the inclined portion 24 for rotating the drum if desired, or for releasing the hair-curling device and removing the same from the head.

In Figures 6 and 7 there is shown a modified form of the invention wherein a winding drum 35 is illustrated comprising a primary jaw 36 and an auxiliary jaw 37. The primary jaw 36 is provided with an extending finger-grip 38 at one end and the primary jaw 36 is rotatably mounted

upon the inwardly extending journal portion 39 of the guiding member 40. The guiding member 40 comprises a pair of parallel rods 41 between which the strand of hair may be fitted and the outer ends of the strands 41 terminate in a right-angularly extending enlarged loop 42 which may be gripped by the finger of the operator for spreading the rods apart to facilitate the placing of the hair therebetween. The opposite ends of the rods 41 terminate in an upwardly and outwardly extending loop 43 which projects in a plane at right angles to the loop 42 and constitutes a means which may be gripped by the fingers to hold the guide 40 in position while the drum 35 is being rotated. A retaining band 44 is used to hold the parallel rods forming the guide 40 in assembled relation.

In Figure 10 there is shown a further embodiment of the present invention which illustrates a protector pad 45 upon which rests a clamp member 46 carrying parallel spring rods 47 secured and fastened together as at 48 by means of a staple, these rods 47 fitting in a position to overlie the longitudinally extending slot 49 formed in the clamp member 46 and the protector pad 45. Each rod 47 is provided with a flaring outer end 50 extending in substantially parallel relation to the sides of the V-shaped notch 51 formed at the outer end of the clamp 46 and protector pad 45. These flaring ends 50 provide means to be engaged by the fingers of an operator to spread the rods 47 apart and to facilitate the placing of the hair therebetween.

In association with the structure illustrated in Figure 10, I provide a special winding drum and locking mechanism, the winding drum being indicated by the numeral 52 and comprising a pair of clamping jaws 53 and 54 of a suitable type. A collar 55 is secured at one end of the drum 52 and an operating key 56 is carried by the drum 52 to rotate the drum within the collar 55. The primary jaw 53 of the drum 52 is provided with a latch-receiving portion 57 at the end opposite to the key 56. This latch-receiving portion is provided with a pair of cross-notches 58. A locking bar 59 is pivotally secured, as at 60, to the collar 55 and is adapted to lie snugly against the drum 52, as shown in Figure 8. A pivoted latch 61 is secured to the outer end of the locking bar 59 and this pivoted latch is adapted to selectively fit in one of the cross-notches 58 of the latch-receiving portion 57 and hold the drum 52 in a selected rotated position. The end of the latch 61 is bent laterally as at 62, and again bent backwardly in the opposite direction, as at 63, to provide a finger-engaging portion to facilitate the placing of the latch 61 into and out of engagement with one of the selected cross-notches 58.

Figures 11 to 13 inclusive, it will be noted, illustrate that the winding drum 52 carries a key or thumb-engaging portion 56, and the collar 55 is loosely mounted upon the drum 52 so that the drum 52 may be freely rotated in counter-clockwise direction within the collar 55. The latch-receiving portion 57 is carried by a shank 57^a which shank 57^a is fitted within the socket 64 formed in the drum 52. This shank 64 carries a ratchet coil spring 57^b one end of which is adapted to frictionally contact the inner wall of the socket 64 and prevent the rotation of the drum 52 in a clockwise direction and permit the rotation of the drum in the direction of the wind of coil 57^b or in a counter-clockwise direction when the finger-engaging portion embodying the elements 62 and 63 are gripped between the

thumb and the first two fingers of one hand of an operator, and when the turning key 56 is gripped between the thumb and first finger of the other hand of the operator. The locking bar 59 is attached to the collar 55 by a fixed pivot 55^a at one end and is attached to the latch 61 by a fixed pivot 61^a so as to firmly anchor the ends of the locking bar 59, but at the same time, because of the spring characteristics of the bar 59 this bar may flex outwardly, as shown in dotted lines in Figure 13, as the hair is rolled about the drum 52.

It should be understood that a very simple and efficient hair curling device is provided which may be very conveniently and quickly locked in position, and which may be used in association with the guiding element to facilitate the winding of hair upon the drum, at the same time efficiently supporting the drum in a position to hold the hair in a wound position upon the drum and closely against the head of the user.

Certain detail changes in the mechanical structure may be employed without departing from the spirit of the invention so long as such changes fall within the scope of the appended claims.

Having described the invention, what I claim as new is:

1. A hair curling device of the class described comprising a drum having means for clamping hair in engagement therewith, a locking bar pivotally supported in connection with the drum and adapted to be swung toward and away from the drum, a latch member pivotally secured to one end of the locking bar, and said drum having oppositely extending cross-latch-receiving notches at one end for receiving said latch to hold the drum in a selected rotated position.

2. A hair curling device of the class described comprising a drum having means for clamping hair in engagement therewith, a locking bar pivotally supported in connection with the drum and adapted to be swung toward and away from the drum, a latch member pivotally secured to one end of the locking bar, said drum having oppositely extending cross-latch-receiving notches at one end for receiving said latch to hold the drum in a selected rotated position, and said latch having oppositely extending finger-engaging portions adapted to extend under the latch-receiving portion to hold the latch against longitudinal movement within the latch-receiving notches.

3. In combination with a protector pad having a longitudinally extending slot, a clamping member engaging the pad and having a longitudinally extending slot registering with the first mentioned slot, spring longitudinally extending hair clamping rods secured at one end to said clamping member and having finger-engaging portions at their opposite ends, and a hair-winding drum associated with said clamping member.

4. A hair curling device of the class described comprising a drum, a hair-guiding member, said guiding member having a journal portion extending into said drum and an outwardly extending finger-engaging loop, an inclined portion carried by the journal portion, said drum having radiating notches for receiving said inclined portion to hold the drum in a selected rotated position, and said inclined portion being selectively movable toward and away from said notches.

5. A hair curling device of the class described comprising a drum, a hair-guiding member, said guiding member having a journal portion extending into said drum and an outwardly ex-

tending finger-engaging loop, an inclined portion carried by the journal portion, said drum having radiating notches for receiving said inclined portion to hold the drum in a selected rotated position, said inclined portion being selectively movable toward and away from said notches, said loop terminating in an underlying leg, a clamping rod secured at one end to said leg, said underlying leg carrying a pivoted latch, and said clamping rod having an outwardly inclined end engageable by the latch for holding the clamping rod in clamped engagement with respect to the underlying leg.

6. A hair curling device of the class described comprising a curling drum having a projecting finger-engaging portion, a guide member comprising parallel guiding rods and an upwardly extending finger-engaging loop, the opposite ends of the rods terminating in a rod-spreading loop projecting transversely of the drum to facilitate the spreading of the rods and to facilitate the placing of the hair therebetween.

7. A hair curling device of the class described comprising a curling drum, a collar journaled at

one end of the drum, a locking bar pivotally secured by means of a fixed pivot to said collar, a pivoted latch secured to the opposite end of the locking bar by means of a fixed pivot, the locking bar being adapted to flex outwardly as hair is rolled upon the drum to firmly contact the hair, a notched member mounted upon the opposite end of the drum for receiving said pivoted latch, and said drum being rotatable in one direction only 5 with respect to the notched member.

8. A hair curling device of the class described comprising a curling drum, rotatable means mounted near one end of said drum, a locking bar pivotally secured at one end by means of a fixed pivot to said rotatable means, a second 15 rotatable means carried by the opposite end of the drum, means for locking the opposite end of the locking bar in engagement with said second rotatable means, and said locking bar being adapted to flex outwardly as hair is rolled upon the drum to firmly contact the hair and frictionally hold the drum in a set position.

JAMES K. CROTTES.
